UNITED STATES PATENT OFFICE.

GUSTAV GOLDMAN, OF BALTIMORE, MARYLAND.

APPARATUS FOR MAKING GARMENT-PADS.

No. 842,093.

Specification of Letters Patent.

Patented Jan. 22, 1907.

Application filed September 27, 1904. Serial No. 226,227.

To all whom it may concern:

Be it known that I, GUSTAV GOLDMAN, a resident of Baltimore, Maryland, have invented a new and useful Improvement in 5 Apparatus for Making Garment-Pads, which invention is fully set forth in the following specification.

This invention relates to means for making garment-pads, and has for its object to provide mechanism whereby garment-pads of 10 various styles and of any desired contour may be automatically manufactured directly from the raw fibrous material.

With this object in view the invention consists in means for forming a continuous sheet or strip of matted or felted fibers of any desired form in cross-section, sizing or otherwise finishing the surface of the sheet or strip, if desired, skiving or cutting out portions 20 from the sheet in order to give the garment-pads the desired taper or slope, cutting the garment-pads from said sheet, and then finishing or smoothing the surface of the pads, the whole forming one continuous and 25 uninterrupted operation.

In my United States Patent No. 758,243 I have described a method of felting or matting masses of fibers together, which, generally stated, consists in laying the fibers down in a 30 light fluffy condition and introducing a dry finely-divided binding material between the fibers and subsequently treating the mass of fibers with the binding material between them in such a way as to convert the dry 35 finely-divided binding material into an active binder, and preferably the apparatus constituting the present invention forms the sheet or strip of matter or felted fibers from which the pads are cut in accordance with 40 the method set forth in my said patent.

To this end the invention, generally stated, consists in means for dividing or separating the fibers into a light fluffy mass combined with means introducing a dry finely-divided 45 material—such as powdered resinate, for example—between the fibers and means subsequently subjecting the mass of fibers to the action of moisture, heat, and pressure, either simultaneously or otherwise, whereby the 50 binding material is converted into an active binder. The fibers are thus converted into a strip or sheet and are transported from one part of the mechanism to another upon continuously-traveling carriers, such as a continuous belt or series of belts.

In the manufacture of many forms of garment-pads the sheet or strip of fibers may be of even thickness in cross-section, while, on the other hand, for certain other forms of pads—as, for example, in the manufacture 60 of sloping or tapered garment-pads—it is desirable that the sheet or strip should be thicker at some portion of its cross-section than at others, preferably tapering from its highest point toward its edges. This thickest portion of the sheet need not be its medial line, but may be at any point between the two edges of the sheet. For the purpose of providing a sheet that is thus of uneven or varying thickness in cross-section I preferably 70 compose the sheet or strip of a series of superimposed films, laying the first film down upon the traveling carrier and simultaneously introducing the binding material among the fibers, after which another film is laid upon 75 the first, the binding material being simultaneously introduced between the fibers of the second film, and so on until a sufficient number of films have been laid one upon another to form a sheet or layer of the desired thickness. Some of these films are of the full 80 width of the desired sheet of finished material, while others are narrower and are placed at the point where the greatest thickness of the finished sheet is desired.

The several films having been placed one upon another, the entire sheet or layer is advanced, preferably by a continuously-moving carrier, to a mechanism (here shown in the form of a steam press or table) where it is 85 subjected to heat and pressure, and in case the binding material is of a character rendering it desirable, also to moisture. The material having been thus subjected to heat, pressure, and moisture, if need be, it is then 90 preferably passed between a pair of steam-rolls for more effectively setting the binding material, and from there, while it is still hot, and before the binding material has finally 95 reached its absolutely-fixed condition, the 100 material may, if desired, be passed between suitable formers which act to smoothly adjust the entire mass, forming the sheet so that its greatest thickness will be accurately 105 adjusted along the line desired, though, if preferred, the treatment by the forming appliance may be omitted. When it is desired to more effectively finish the sheet so as to give the exterior surfaces a smooth and presentable finish, it is preferably subjected to 110

heat and pressure, as with a series of hot finishing-rolls.

In the manufacture of certain classes of garment-pads it is desirable that the material should not only slant from the medial line out toward the edges of the sheet or strip, but it is also desirable to have the same accurately taper off from the highest point in the finished pad, and by the present invention the strip of material as it proceeds from the finishing-rolls is fed directly to a mechanism which cuts or skives out on tapered lines a portion of the thickness of the sheet, the particular contour of the portion skived out being determined by the particular character or class of pad it is desired to construct. The skiving mechanism acts to skive out transverse pieces from one side of the sheet, preferably the material between the skived portions being sufficient for a pair of said pads. After the sheet of material passes from the skiving mechanism it is advanced to suitable means for cutting pads of the desired shape therefrom. Any suitable means may be employed for this purpose; but I prefer to employ a die designed to simultaneously cut a pair of pads from the strip of material at a single stroke, means being provided for causing a dwell in the advance movement of the fibrous strip during the time in which the die is effecting the cut. During the skiving operation the surface acted upon by the skiving mechanism is liable to be more or less roughened up, and for the purpose of giving the pads a smooth and finished appearance they are passed to a finishing device so constructed that the same finishes one surface of the pad as it passes through the device, after which the pad is again presented by suitable means, such as a turn-table, to the finishing device, and its other face being finished it is then delivered onto a suitable carrier by which, after being carried a proper distance to cool and allow the binding material to set, it is deposited in a hopper or in a pile, from whence it is removed at intervals by the workmen.

Any suitable means may be employed for separating the fibers into a light fluffy mass. Preferably a carding-machine of the usual or any suitable construction is employed for this purpose, and as the fibers leave the doffer of the carding-machine they pass under a suitable apparatus for distributing the finely-divided binding material directly upon the fibers as they are in the act of falling upon the continuous carrier. Means are employed for evenly distributing the fibers across the continuous carrier (which is preferably an endless belt or series of such belts) as they leave the doffer of the carding-machine, and for the purpose of insuring the even width of the sheet the fibers pass between suitable guide-plates onto the continuous carrier. By adjusting the guide-plates of the

several carding-machines, which may be arranged in series, it will be perceived that it is entirely practicable to lay down first a broad or foundation film of the fibers upon the traveling carrier and then at the next carding-machine to lay down a narrower film—say one of two-thirds the width of the first film—and by suitably guiding the second film it may be placed either centrally upon the first film or to one side of the central line along any desired line. Other films may be laid upon the second film, either narrower or wider than the second, and finally a top film may be placed over the whole, which may be and preferably is of the full width of the first film. When the sheet thus formed is subjected to means for converting the binding material between the fibers of the several films into an active binder, the various films will all be united into one coherent, matted, or felted mass of uneven thickness, or in case all of the films laid down are of equal width into a sheet of uniform thickness in cross-section.

If desired, any intermediate film or films may have the binding material omitted and the binding material be supplied to the top and bottom films only. For the purpose of subjecting the sheet or layer when formed to heat and pressure and where desired to moisture for the purpose of converting the binding material into an active binder various forms of apparatus may be employed. Preferably, however, the sheet is advanced from the continuous carrier between two belts, one of which is a moisture-carrying belt, and these two belts carry the fibers upon a steam-heated table, upon the surface of which rolls are mounted and actively revolved, said rolls being preferably cut out upon their surface to suit their contour in cross-section to the sheet which is being manufactured and the rolls also being preferably heated, as by steam, and provided with means for adjusting them toward and from the table in order to regulate the pressure with which they may bear upon the sheet as the said sheet is advanced beneath them. Instead of laying down the fibers and afterward introducing dry binding material between them, as set forth in my United States Patent No. 758,243, the mass of fibers may be treated with a wet binder and afterward laid down in sheet form by any suitable means, as a carding-engine, and then subjected to heat and pressure, as set forth in my United States Patent No. 768,599. In this case the belt employed with the steam-table would not act to impart moisture to the fibers, but to extract it therefrom, or, if desired, it might be omitted altogether and a simple conveying-belt substituted therefor.

Various means may be employed for shaping the sheet in cross-section after it leaves the steam-press table, one very efficient

means for this purpose consisting in a conical roller or rollers bearing upon the top of the sheet, which may be supported from beneath by any suitable roller, the action of the conical roller being to crowd the fibers while the binding material is yet unset into the position which it is desired they should ultimately occupy, thereby giving the sheet in cross-section its final form. Preferably also 10 a forming device, as a pair of conical rollers, acts upon the sheet or layer of material just before it passes upon the steam-table, serving to crowd the fibers of the entire sheet approximately into the final form—*i. e.*, to give 15 the whole sheet the cross-sectional form which it is desired it should have when completed.

After the sheet has passed the steam-press table and the former there are liable to be stray fibers, which project from the surface 20 of the sheet, and for the purpose of smoothing these down and giving the sheet a finished appearance the sheet is preferably passed through a finishing device consisting, essentially, of a pair of finishing-rolls. Any 25 suitable means for finishing the sheet after it leaves the steam-press table and forming-rollers may be employed; but preferably the sheet is first passed over the top of a large heated finishing-roll having a plurality of small 30 steam-heated rollers bearing thereon, and the action of these is to finish one surface of the sheet, and from the first finishing-roll the sheet is then passed underneath a second finishing-roll, which operates in connection 35 with a plurality of steam-heated rollers to finish the opposite surface of the sheet.

The carding engines or machines employed for laying down the fibers in a light fluffy condition may be placed either side by side with 40 the continuous carrier passing in front of the doffer of each machine or the carding-machines may be placed one in front of the other with the continuous carrier passing underneath the series of machines and beneath the doffer of each machine. When the latter arrangement is employed, the sheet of material manufactured may be the full width of the doffer of the carding-engine, if desired, or by removing some of the teeth of the 45 doffer or of the doffer-comb, thereby dividing the same into sections of any desired width, a plurality of sheets or strips of material may be simultaneously laid down upon the traveling carrier.

50 In cases where it is desirable to "size" the surfaces of the sheet suitable means are employed for applying a liquid or other size. Preferably this is done just before the sheet enters the finishing-rolls, though this is not 55 essential.

Instead of "sizing" the surfaces of the sheet by supplying a size thereto a liquid or gaseous solvent for the binding material may be sprayed or otherwise applied to the 60 surfaces of the sheet, thereby softening the

binder and causing it to so engage the projecting fibers as to afford a smooth surface under the action of the finishing-rolls.

The inventive idea may receive a great variety of mechanical expressions. One of these is illustrated in the accompanying drawings, in which—

Figure 1 shows a carding-engine in front elevation having a suitable dusting device mounted thereon for distributing the binding material among the fibers as the same leave the doffer of the carding-machine, and the steam-press table in side elevation, disclosing the manner in which the sheet of fibers is subjected to heat and pressure, and moisture, if 70 desired. Fig. 2 is a broken plan showing one manner of evenly distributing the fibers upon the traveling carrier from the doffer of the carding-machine. Fig. 3 is a similar broken plan showing another arrangement for the 75 same purpose. Fig. 4 is a cross-section on the line 4 4, Fig. 1, showing the fibers as they leave the doffer of one machine preparatory to being superimposed upon three other films already in position upon the continuous carrier. Fig. 5 is a section on the line 5 5, Fig. 1, showing the film that is leaving the doffer in 80 Fig. 4 just as it is in the act of being placed or superimposed upon the other films on the continuous carrier. Fig. 6 is a detail showing 85 the guide-plates by means of which the films from the doffer may be placed in any position and of any desired width upon the continuous carrier. Fig. 7 shows in longitudinal section a pair of conical rollers that are employed to press the various films on the 90 continuous carrier into approximately the form in cross-section which it is desired the finished sheet shall have after it has passed the steam-press table. Fig. 8 is a diagrammatic 95 plan showing the manner in which a plurality of strips may be simultaneously laid down with the carding-engines placed one in advance of the other; and Fig. 9 is a diagrammatic illustration of the arrangement of the 100 apparatus when a plurality of carding-machines are arranged side by side, showing also in diagrammatic form the steam-press table, the former, the sizing apparatus, finishing-rolls, the skiver, the die-press, and the 105 finishing-press.

Referring to the drawings, 1 indicates any suitable mechanism for separating the fibers into a fine fluffy mass and laying them down upon any suitable support. As here shown 110 this mechanism 1 is in the form of a carding-machine of any usual or suitable construction, and for the purpose of diagrammatically illustrating the invention I have shown in Fig. 9 a series of these machines, (indicated by 115 the respective numerals 1, 2, 3, and 4.)

Referring to Figs. 1, 2, and 3, 5 indicates the doffer of a carding-machine from which the carded fibers are delivered, preferably onto an endless belt 6, which serves to carry the 120

fibers as they are delivered from the doffer slightly outward therefrom, and 7, Fig. 9, indicates a continuous carrier, here shown in the form of an endless belt, which passes 5 along in front of the carding machine or machines. If the carded fibers were permitted to fall directly upon the continuous carrier 7, they would not be evenly distributed across the carrier, and the width of the sheet or layer 10 of fiber falling thereon could not be accurately controlled. In order that the fibers as they fall from the carding-machine 1 may be distributed across any desired width or portion of the continuous carrier 7, suitable means 15 are provided for laying the fibers down upon the continuous carrier 7 across the entire width or any desired portion thereof. Various mechanisms may be employed for this purpose, and there is shown in Fig. 2 an end- 20 less belt 8, arranged to move in front of the doffer of the carding-machine, but at a slight angle thereto and in a plane above the continuous carrier 7. When the fibers pass from the doffer of the carding-machine, they are 25 received by the continuous belt 6, and after passing from said belt they drop upon the distributing-belt 8, as will be clearly understood from an inspection of Figs. 2 and 4. This belt 8, however, is so arranged that its 30 rear edge on one side of the carding-machine is immediately under the outer portion of the belt 6, and the fibers falling from said belt 6 are received on the inner portion of said distributing-belt 8. The inner edge of 35 the belt 8, however, slants in considerably toward the doffer of the carding-machine and to such an extent that the outer edge of said belt is brought approximately under the outer edge of the belt 6 at the advance side of 40 the carding-machine—*i. e.*, on the side in the direction in which the carrier 7 is traveling. The distributing-belt 8 also has movement in substantially the same direction as the carrier-belt, and as it thus moves in a line across 45 the line in which the fibers fall it will be seen that this results in the fibers being evenly distributed across the entire width of the belt 8 as it advances.

Referring to Figs. 4, 5, and 6, 9 and 10 indicate upright guide-plates between which the fibers on the distributing-belt 8 pass as said belt advances, said guide-plates being adjustably mounted upon the framework of the mechanism by any suitable means, as slotted 50 bars 12, through which adjusting-screws 13 are passed, to the end that the guide-plates may be moved toward or from each other, as may be desired, to lay down a sheet of fiber of greater or less width. Instead of thus 55 passing the fibers from the doffer of the carding-machine onto a distributing-belt placed diagonally to the carding-machine the same result may be effected by placing an apron in front of the carder, which apron has its front 60 edge arranged at an angle to the line of travel 65

of the continuous carrier, as shown in Fig. 3, where the fibers are shown as passing from an apron 14, whose front is shown arranged at an angle to and above the continuous carrier 7. As shown in said figure, it will be seen 70 that on the advance or right-hand side of the carding-machine the fibers are deposited on the outside portion of the continuous carrier 7, while at the rear or left-hand side of the figure the fibers are deposited upon the inner 75 portion of the carrier, the ultimate result being an even distribution of the fibers entirely across the carrier. The guide-plates 9 and 10 having been adjusted to the desired width, the fibers as they are advanced by distributing-belt 8 of Fig. 2, or as they are advanced by the continuous carrier 7 in the construction shown in Fig. 3, are passed between the plates, and the ultimate width of the film of fibers laid down upon the continuous carrier 80 will thus be determined by the adjustment of the guide-plates 9 and 10. As the fibers pass from between said guide-plates they are received between two continuously-revolving rollers 15 and 16, Fig. 5, driven by any suitable gearing, and are deposited by said rollers directly upon the continuous carrier or upon another film of fibers previously laid 85 upon the carrier.

Referring to Figs. 1 and 2, 17 indicates a 90 suitable mechanism for receiving and evenly distributing the finely-divided binding material among the fibers as they pass from the doffer 5 of the carding machine and along the belt 6 just previous to being deposited therefrom upon the carrier-belt. Any suitable mechanism for distributing the binding material in a uniform manner among the fibers may be utilized for this purpose; but preferably there is employed a dusting device or 95 apparatus of the character shown and described in my United States application, Serial No. 225,538, filed September 22, 1904. This device is supported in any suitable way upon the framework of the carding-engine 1, 100 and as the fibers leave the doffer of the carding-machine the binding material is uniformly distributed between them.

The movements of the various belts and portions of the machinery would be liable to 105 disturb the fibers which have been laid down upon the continuously-advancing carrier, and in order to avoid this means, such as an endless belt 18, are supported in a position immediately over the continuous carrier, 110 which belt is capable of being adjusted up or down to receive an advancing sheet of the fibers, whatever the thickness of said sheet 115 may be. In front of the second carding-machine of Fig. 9 this retaining-belt would be 120 high enough to receive and retain a single film of the fibers which had been deposited by the previous carding-machine 1. In front of the machine 3 this belt might be adjusted so 125 as to receive between it and the carrier-belt 130

two films, and so on throughout the series of carding-machines.

The operation of the apparatus as thus far described is as follows: The continuous carrier being set in motion, the duster-box 17 being supplied with a suitable finely-divided binding material, and the carding-machine 1 being set in operation, a film of fiber leaving the doffer of the machine passes over the apron 6, and as it does so the duster 17 distributes the finely-divided binding material between the fibers. The fibers with the binding material between them then pass from the apron 6 upon the distributing-belt 8, Fig. 2, by which they are advanced from left to right between the guide-plates 9 and 10. At the carding-machine 1 these plates are set at a distance apart corresponding to the desired width of the sheet of material to be produced. As the film 8 leaves the guide-plates 9 and 10 it is passed between the rollers 15 and 16, situated immediately to the right of the carding-machine 1, by which they are compressed into a somewhat smooth and compact mass and delivered immediately upon the continuously-advancing carrier 7, which moves from left to right. As this carrier advances the film is carried under the retaining-belt 18, in front of the second carding-machine, and this machine being then set in motion a second film of the fibers with the binding material between them is deposited from between the rollers 15 and 16 thereof directly upon the film of fibers laid down by the carding-machine 1. This second film of fibers may be of the same width as the first film, or, if desired, it may vary in width. For the purpose of illustration it is shown at 20, Fig. 4, as being slightly narrower in width and as being placed approximately in the middle of the first film 19. This, however, need not be done, as the second film may be placed to either side of the center of the first film, if desired. This operation is repeated by each carding-machine in succession, the film from each carding-machine being laid down upon the film deposited by the previous machine, the width of the various films being determined entirely by the adjustment of the guide-plates 9 and 10. It will be understood, of course, that if desired only a single carding-machine may be operated, in which case a sheet of the thickness of one film only would be formed. The sheet of fibers consisting of one or more films, as the case may be, having been deposited upon the continuous carrier is advanced by it and delivered over a roller 22, Fig. 7, above which there is mounted a pair of rollers 23 and 24. As here shown, these rollers 23 and 24 are conical in shape and have their apices placed adjacent to each other above the roller 22 and are mounted upon shafts capable of adjustment around universal joints 25 and 26, to the end that the apices of the

rollers may be raised or lowered, as may be desired. The conical rollers are preferably of uneven length, the rollers 24 being here shown as considerably longer than the roller 23, though, if desired, they may be of the same length. As the sheet of fibers is advanced by the roller 22 under the conical rollers 23 and 24 the latter act to crowd the fibers in such a way as to cause the highest point of the sheet of fibers when taken in cross-section to be immediately under the apices of the two rollers, the two conical rollers thereby serving to give the general form to the sheet in cross-section. The sheet of fibers having thus been formed or shaped is delivered from under the conical rollers to the mechanism for converting the dry finely-divided binding material to an active binder for the fibers. The particular operation of this mechanism will depend somewhat upon the character of the binding material employed. In some cases it will be found desirable to supply moisture, and generally in connection with heat and pressure, while in other cases the moisture may be omitted and heat and pressure alone resorted to.

Referring more particularly to Fig. 1, 27 is an endless belt passing around rollers 28, 29, 30, and 31. This belt may be of any suitable construction calculated to receive and carry moisture, preferably of the construction shown and described in my application, Serial No. 225,539, filed September 22, 1904. This belt travels in the direction indicated by the arrow, and immediately above it to the right of the conical rollers 24 is a second belt 32, traveling in the direction indicated by the arrow. The sheet of fiber as it is delivered from the roller 24 is advanced between the belts 27 and 32 and carried upward upon a table 33, which table is heated by a steam-box 34, supplied with steam in any suitable manner, as through steam-pipes 35. The sheet of fibers is advanced along the steam-table 33 by the belt 27 and a belt 36. Mounted immediately above the table are a series of steam-heated rollers 37, which rollers are preferably adjustable toward and from the surface of the table 33 and which have their peripheries cut away so as to conform to the particular shape in cross-section of the sheet of fibers which is to be formed. Located at any suitable place along the travel of the belt 27 is a suitable means for supplying moisture thereto, here shown as a jet 38, which discharges moisture in the form of steam or water, as may be desired, upon the belt.

The operation of this portion of the apparatus is as follows: The belts 27, 32, and 36 being in operation and moving in the direction indicated by the respective arrows, the jet 38 discharging moisture upon the belt 27, and the table 33 and the rollers 37 being suitably heated by steam or otherwise, the sheet of fibers is advanced from the carding-engine 130

upward and along the top of the steam-table 33. The moisture in the belt 27 is converted into steam by the heat of the table 33 and rollers 37 and penetrates throughout the 5 mass of the fibers, thus serving in conjunction with the heat to convert the dry finely-divided binding material into an active binder, and the pressure of the rollers upon the sheet of fibers serves to render this binding 10 condition of the material effective for the purpose desired. This operation is repeated as the sheet of fibers passes under the several rollers 37 of the series until it emerges from the last roller at the right-hand side of Fig. 1. 15 At this point the moisture has thoroughly permeated the entire sheet, the binding material has become thoroughly affected by the heat and the moisture, so as to render it an active binder, and the heat present in the 20 sheet will serve to rapidly drive off the moisture, and as soon as the same has cooled the binding material sets and the fibers are retained in a compact matted or felted mass. It has been found desirable, however, before 25 this cooling and drying action has been completed to again subject the sheet to the action of a suitable forming device. Any suitable device for giving the sheet the desired outline in cross-section may be employed, 30 here indicated in Fig. 9 as a conical roller 40 immediately above a cylindrical roller 41, a pair of steam-rollers 42, interposed between the steam-press table and the former, serving to maintain the binding material hot 35 and the entire sheet in a condition to be suitably acted upon by the former-roller 40.

In case the sheet of fibers is to be "sized" the sizing is preferably done at this point. Any suitable apparatus and any desirable 40 kind of sizing may be employed. For the sake of illustrating the invention I have shown spraying-nozzles *x* and *y* located one above and one below the sheet of fibers, in position to direct a liquid sizing material 45 upon the upper and lower surfaces of the sheet.

In some instances as the equivalent of sizing the surface of the sheet before passing it over the rollers 44 and 45 a suitable solvent 50 for the binding material used is sprayed or otherwise directed onto the surfaces of the sheet, thereby softening the binder, so that it will be peculiarly effective in seizing upon and retaining the stray projecting fibers 55 when the sheet is passed over the rollers 44 and 45. The means for applying the solvent may be of any form desired; but preferably the spray-nozzles *x* *y* are employed for this 60 purpose, the kind of solvent used depending upon the binder that is employed. For example, if a resinate is employed as the binder alcohol, turpentine, or naphtha may be sprayed or directed in gaseous jets upon the surfaces of the sheet.

65 After the sheet has received the desired

form in cross-section from the former-rolls 40 and 41 and without regard to whether the sizing has been applied or not there is liable to be more or less loose fibers projecting from the surface, which would mar its finish. In 70 order to impart smooth and slight finish to the surface of the sheet, it is next passed through a finishing apparatus, which may consist of two large finishing-rolls 44 45, Fig. 9. Any suitable form of finishing apparatus 75 might be employed; but preferably there is employed finishing-rolls heated by steam and operated after the manner described in my application, Serial No. 231,117, filed November 2, 1904. This apparatus, generally 80 speaking, consists of the two large rollers 44 and 45, which are heated, as by steam, and in juxtaposition to the upper surface of roller 44 there is a series of smaller rollers 46, also steam-heated, so that the sheet of fibers as it 85 passes between the roller 44 and the rollers 46 has one of its surfaces—as the lower surface, for example—smoothly finished by the action of the roller 44, and as the sheet leaves roller 44 it passes under roller 45, 90 where it is subjected to the finishing action of said roller 45 to finish the other surface. The sheet of fibers having thus been laid down suitably formed, the fibers thereof 95 bound together, and the surface of the sheet sized, if desired, and properly finished, it is then passed upon any suitable conveyer—as, for example, the conveying-belt 48, Fig. 9—where it is allowed to travel some distance in the air for the purpose of cooling off and setting the binding material. The sheet of fibers is next passed to mechanism for shaping it so as to suit it for having pads cut therefrom. In the formation of pads, such as coat-pads, the sheet will be preferably 105 constructed with its highest point either along its medial line or to one side thereof, as might be desired in the particular class of pads, and would slope from this line toward the two edges of the sheet. In order to give 110 the particular sloping form to the finished pad, it is designed by the present invention to skive out or cut away a portion of the thickness of the finished sheet, and for this purpose the sheet is passed directly from the 115 conveying-belt 48 to any suitable skiving apparatus 49, preferably of the form shown in my application, Serial No. 226,226, filed September 27, 1904.

The skiving apparatus operates to cut out or remove segmental sections at stated intervals from one surface of the sheet. The skiving is performed in such manner that the skived-out portion tapers in the manner which it is desired the finished pad shall taper, and the result of the skiving and of the tapering of the sheet of fibers from an intermediate line toward both of its edges is a portion of the sheet which slopes or tapers in all directions from the highest or intermediate 125 130

point. For the purpose of skiving the sheet in the manner described I prefer to employ a skiving apparatus consisting, essentially, of a rapidly-moving endless cutter-knife, Fig. 9, which has a line of motion transverse to that of the sheet and immediately beneath the under surface of the sheet as it is advanced. Immediately adjacent to the skiving-knife the sheet passes between two rollers, the upper one, 49', of which is mounted so that it bears by spring or gravity pressure upon the lower roller, which latter roller has a portion 49" of its surface cut away, the contour of the cut-away portion corresponding to the contour of the skive which it is desired to cut out of the sheet. As the sheet passes between these rollers the gravity-roller acts to press the fibers of the sheet down into the cut-out portion 49" of the lower roller and to that extent below the level of the skiving-knife, and as the sheet is thus advanced with a portion thereof depressed below the level of the knife the knife acts to cut away the portion which is depressed below the normal level, the shape 25 of the skived-out or cut-away portion corresponding exactly to the contour of the depression in the lower roller. The sheet having been thus skived is in condition to be presented to the mechanism for cutting out the pads. Various forms of devices for this purpose would readily suggest themselves; but I prefer to employ a die-press of the construction shown in my application, Serial No. 226,594, filed September 29, 1904. This die-press consists, essentially, of a rigidly-mounted hollow cutting-die 50, standing in a substantially vertical plane, and a vibrating platen 50', operated to advance to and recede from the die 50, together with apparatus, as 30 feed-rollers 50", for feeding the skived sheet between the die and the platen. In order that the die may cut the pads exactly at that portion of the sheet that has been skived out for that purpose and so that the tapering of the pad may be of the form desired, it is essential that the sheet should be fed before the die in exactly the proper position, and for this purpose means are provided in the die-press for elevating or lowering the feed-rollers 50" so as to properly position the sheet before the die. Moreover, at the instant when the die is operating to cut the pads from the sheet it is essential that there should be a dwell in the feed mechanism which advances the sheet to the die, and for this purpose the die-press is provided with suitable clutch mechanism (not shown) for throwing the feeding-rollers out of action at the instant when the platen is advanced against the die, 45 and vice versa, for throwing the feed-rollers into action at the instant when the platen recedes from the die.

For the purpose of enabling the pads to be readily delivered from the die-press and for 50 expedition of action the die 50 is made hol-

low. It may be and preferably is formed so as to cut two pads at a time from the sheet. As the pads fall from the hollow die they are received by a continuous carrier, which acts to advance them to a finishing-press. The treatment of the pads in the finishing-press is rendered desirable by reason of the fact that the action of the skiver is liable to leave a more or less rough and unfinished surface at the point where the skiving-knife has cut through the material, thereby giving the same an unsightly appearance. In order to effectually smooth the pad upon both surfaces and complete it for the market, it is advanced to the finishing-press, which is constructed to subject the pad to heat and pressure, the heat serving to soften the binding material slightly at the surface and the pressure causing the projecting fibers to be forced firmly into place, thus imparting the desired finish to the pad.

Any suitable finishing device may be employed; but preferably I employ that shown in my application, Serial No. 231,116, filed November 2, 1904. This finishing-press consists, essentially, of a convex heated roller 51, revolving in close proximity to a heated concave surface 51", and a built-up or padded belt 51', so constructed that in cross-section it presents a concave surface corresponding approximately to that of the shape of the pad to be finished. The pad is received by this hollowed-out or concave belt 51' and by it carried under the hot roller 51 and between said roller and the hot concave surface of table 51" above referred to. This acts to smoothly finish one side of the pad, and as it emerges from the belt and roller it is delivered to a turn-table 52, which acts to deliver it to an elevator-belt 53, by which it is delivered to a second concave carrying-belt, which carries it again beneath the hot roller 51 and hot concave surface 51", whereby the other surface of the pad is finished. As the pad emerges from between said second belt and the roller it is deposited by a chute 54 upon a suitable slowly-moving carrier 55, by which it is deposited in a suitable receptacle 56 or in a pile to be removed by the workmen. Preferably this carrier is one 115 extending a considerable distance in order that the pad may be allowed to cool before it is subjected to any rough treatment, thereby insuring the permanency of the finish imparted by the finishing-press.

Operation: The operation of the mechanism as a whole will be readily understood. The fibers being laid down on the continuous carrier by the carding mechanism or mechanisms and the binding material simultaneously introduced between the fibers by the duster mechanism are treated by the forming-rollers 23 and 24 to crowd the same into approximately the desired form in cross-section, after which it is advanced to the steam-

table, which acts to convert the binder into an active binding agent for the fibers. When the sheet emerges from the steam-press-table, it preferably passes between steam-rollers, 5 which serve to maintain the heat in the mass of fibers, thereby leaving it in the best condition to be acted upon by the former, consisting of the supporting-roller 41 and conical or inclined roller 40. If it is desired to size the 10 sheet at this point, the nozzles *x* and *y* deliver any suitable sizing, as a very thin liquid glue, upon the upper and lower surfaces of the sheet, thereby supplying the material necessary to bind the little ends and fibers 15 which may project from the sheet just before the sheet advances to the finishing-rollers. These by reason of their heated condition and the pressure to which the sheet is subjected between the first finishing-roll 44 and 20 the pressure-rolls 46, operating in conjunction therewith, serve to effectually finish the lower surface of the sheet, while the hot finishing-roll 45, acting in conjunction with the smaller rolls 47, serve to impart a like finish 25 to the upper surface of the sheet. In case it is not desired to supply sizing to the surface of the sheet this may be omitted, and instead of sizing there may be supplied to the upper and lower surfaces of the sheet, through the 30 jet pipes or nozzles *x* and *y*, a solvent for the particular binder employed, this solvent acting to soften the binder on the immediate surface of the sheet, and thereby rendering it particularly efficient in seizing and tying 35 down projecting ends of the fibers as they are subjected to the action of the finishing-rolls 44 and 45. In case a resinate is employed as the binder the solvent directed by the nozzles *x* and *y* against the surface of the sheet 40 may be either turpentine, naphtha, alcohol or the vapors of alcohol, or any suitable gas. The sheet having been thus effectually smoothed upon its surfaces by the finishing-rolls is then advanced to the skiving mechanism, which serves to regularly skive out 45 the sheet, thereby placing it in condition for the action of the cutting mechanism or die-press, and the pads having been delivered by the die-press to the carrier in front of the 50 same they are by this carrier delivered to the finishing-press, which after effectively smoothing them on both sides delivers them to the off-bearing carrier 55.

It will thus be seen that the mechanism as 55 a whole acts to take the raw fibers and binding material and by a continuous operation convert the same into finished pads ready to be placed upon the market.

It will be readily understood that if it is 60 desired to utilize the sheet of fibrous material for other purposes it may be treated as a finished product either after it leaves the steam-press, or preferably after it leaves the finishing-rolls, and the skiving operation, the

cutting by the die-press, and the finishing of 65 the cut pads may be omitted.

The specific construction of the steam-press table, the finishing-rolls, the skiver, the die-press, and the finishing-press, as well as that of the duster or binder-distributing 70 mechanism, is not specifically claimed herein, since the same forms the subject-matter of other applications.

What is claimed is—

1. In an apparatus of the character de- 75 scribed, the combination of means for laying the fibers down in a light, fluffy condition, with means for introducing dry finely-divided binding material between the fibers.

2. In an apparatus of the character de- 80 scribed, the combination of means for laying the fibers down in a light fluffy condition, with means for evenly distributing dry finely-divided binding material between the fibers.

3. In an apparatus of the character de- 85 scribed, the combination of means for laying the fibers down in a light fluffy condition, with means for introducing dry finely-divided binding material between the fibers, and means subsequently converting said binding 90 material into an active binder for the fibers.

4. In an apparatus of the character de- 95 scribed, the combination of means for separating the fibers into a light fluffy mass, means introducing dry finely-divided binding mate- 95 rial into said mass, and means supplying heat and moisture to said mass.

5. In an apparatus of the character de- 100 scribed, the combination of means for separating the fibers into a light fluffy mass, means introducing dry finely-divided binding 100 material into said mass, and means subjecting said mass to heat, moisture and pressure.

6. In an apparatus of the character de- 105 scribed, the combination of means laying the fibers down in a plurality of superimposed films or layers, and means introducing dry 110 finely-divided binding material between the fibers.

7. In an apparatus of the character de- 115 scribed, the combination of means laying the fibers down in a plurality of superimposed dry finely-divided binding material between the 115 fibers of each film or layer as the same is laid down.

8. In an apparatus of the character de- 120 scribed, the combination of means laying the fibers down in a plurality of superimposed films or layers, means introducing dry finely-divided binding material between the fibers of each film or layer, and means converting 120 said binding material into an active binder for the fibers.

9. In an apparatus of the character de- 125 scribed, the combination of means laying the fibers down in a plurality of superimposed

- films or layers, means introducing dry finely-divided binding material between the fibers of each film or layer, and means subjecting said superimposed films or layers to heat and pressure. 5
10. In an apparatus of the character described, the combination of means laying the fibers down in a plurality of superimposed films or layers, means introducing dry finely-divided binding material between the fibers of each film or layer, and means introducing moisture between the fibers of said superimposed films or layers. 10
11. In an apparatus of the character described, the combination of means laying the fibers down in a plurality of superimposed films or layers, means introducing dry finely-divided binding material between the fibers of each film or layer, and means introducing moisture between the fibers of said films or layers and simultaneously subjecting said fibers to heat and pressure. 15
12. In an apparatus for making garment-pads of fibrous material, the combination of means laying the fibers down in a continuous strip or layer, means introducing binding material between the fibers, and means cutting the pads from said strip or layer. 20
13. In an apparatus of the character described, the combination of means laying the fibers down in a continuous strip or layer, means introducing dry finely-divided binding material between said fibers, and means subjecting the said strip or layer to heat and pressure. 25
14. In an apparatus for making garment-pads of fibrous material, the combination of means laying the fibers down in a continuous strip or layer, means introducing dry finely-divided binding material between said fibers, means subjecting the said strip or layer to heat and pressure, and means cutting the pads from said strip or layer. 30
15. In an apparatus of the character described, the combination of means forming the fibers into a strip or layer, means introducing dry finely-divided binding material between the fibers, means converting the dry binder into an active binder for the fibers, and means finishing or smoothing the surfaces of the strip or layer. 35
16. In an apparatus of the character described, the combination of means forming the fibers into a strip or layer, means introducing dry finely-divided binding material between the fibers, means converting the binding material into an active binding material, and means forming or shaping the sheet in cross-section. 40
17. In an apparatus of the character described, the combination of carding mechanism, a dusting device, and forming means for imparting the desired cross-sectional form to the sheet or layer of fibers. 45
18. In an apparatus of the character de- 50
- scribed, the combination of carding mechanism for forming the fibers into a strip or layer, a dusting device for introducing binding material between the fibers, and a moisture-carrying device for converting the binding material into an active binder. 70
19. In an apparatus of the character described, the combination of carding mechanism for forming the fibers into a strip or layer, a dusting device for introducing binding material between the fibers, and a heat and pressure device for treating said strip or layer. 75
20. In an apparatus of the character described, the combination of a carding mechanism for forming the fibers into a strip or layer, a dusting device for introducing binding material between the fibers, a moisture-carrying device and a heating and pressing means for treating said strip or layer. 80
21. In an apparatus of the character described, the combination of a carding mechanism for forming the fibers into a strip or layer, a binder-distributing device for introducing binding material between the fibers, a source of heat and pressure for treating said strip or layer, and means skiving out or removing transverse segments or parts from one surface of the formed strip or layer. 85
22. In an apparatus for making garment-pads, the combination of a carding mechanism, a binder-distributing device, a source of moisture, heat and pressure, means skiving out or removing transverse segments or parts from one surface of the formed strip or layer, and a die-press for cutting the pads from said skived strip or layer. 90
23. In an apparatus of the character described, the combination of a carding mechanism, a continuous carrier moving parallel with the doffer of the carder, and a continuous distributing-belt moving at an angle across the carrier and receiving the fibers from the doffer and depositing them upon the carrier. 95
24. In an apparatus of the character described, the combination of a carding mechanism, a continuous carrier moving parallel with the doffer of the carder, a continuous distributing-belt interposed between the doffer and carrier and moving in a line at an angle to said doffer and carrier, and receiving the fibers from the doffer and depositing them upon the carrier. 105
25. In an apparatus of the character described, the combination of a carder, a continuous carrier moving parallel with the doffer of the carder, a distributing-belt receiving the fibers from the carder and distributing them in the form of a sheet or layer across the carrier, and means regulating the width of said sheet or layer. 115
26. In an apparatus of the character described, the combination of a carder, a continuous carrier, and a distributing-belt re- 125
- 130

ceiving the fibers from the carder and distributing them across the carrier.

27. In an apparatus of the character described, the combination of a carder, a carrier, an apron-belt receiving the fibers from the carder, and a duster or binder-distributing device above the apron-belt.

28. In an apparatus of the character described, the combination of a carder, a carrier, an apron-belt in front of the doffer of the carder, a duster above said apron-belt, and means receiving the fibers from said apron-belt and distributing them across the carrier.

29. In an apparatus of the character described, the combination of a carder, a carrier, an apron-belt in front of the doffer of the carder, a duster above said apron-belt, means receiving the fibers from said apron-belt and distributing them across the carrier, and means regulating the width of the layer of fibers thus deposited on the carrier.

30. In an apparatus of the character described, the combination of a carder, a carrier receiving the fibers in sheet or layer form from the carder, and forming means for shaping the sheet into the desired form in cross-section.

31. In an apparatus of the character described, the combination of a carder, a carrier receiving the fibers in sheet or layer form from the carder, and a pair of conical rollers acting on one surface of said sheet or layer to give it a substantially triangular form in cross-section.

32. In an apparatus of the character described, the combination of a fiber-distributing mechanism, a carrier, and a pair of conical revolving rollers extending toward each other above the carrier.

33. In an apparatus for making garment-pads, the combination of a carder, a duster for introducing binding material between the fibers, means supplying heat, moisture and pressure to the fibers, a die-press for cutting the pads from the matted or felted strip, and means for smoothing or finishing the surfaces of the pads.

34. In an apparatus for making garment-pads, the combination of a carder, means introducing and setting binding material between the fibers, means finishing the surfaces of the strip or sheet, means skiving out sections from one of the surfaces thereof, a cutter for cutting the pads from the skived strip, and means for smoothing or finishing the surfaces of the pads.

35. In an apparatus for making garment-pads, the combination of means laying down a strip or sheet of fibers, means introducing binding material between the fibers whereby the same are united into a sheet, and means automatically cutting the pads from said sheet.

36. In an apparatus for making garment-pads, the combination of means forming a

sheet of fibers tapering from its intermediate portion toward its edges, means transversely skiving one side of said sheet at regular intervals, and means cutting or stamping out pads from said sheet.

37. In an apparatus for making garment-pads, means forming a fibrous sheet of uneven thickness in cross-section, with means automatically stamping or cutting pads from said sheet.

38. In an apparatus for making garment-pads, the combination of means forming a fibrous sheet tapering toward both of its edges from an intermediate thicker portion, with means stamping or cutting pads from said sheet.

39. In an apparatus for making garment-pads, the combination of means for forming a fibrous sheet tapering from an intermediate portion toward its edges, means for sizing the surfaces of said sheet when formed, with means for automatically cutting the pads from said sheet.

40. In an apparatus for forming garment-pads, the combination of means for forming a fibrous sheet of material, means automatically cutting or stamping the pads therefrom, with an automatic device for smoothing or finishing the surfaces of the pads.

41. In an apparatus for forming garment-pads, the combination of means laying down a sheet of fibrous material, means for subjecting said sheet to heat and pressure, and means automatically cutting the pads from said sheet.

42. In an apparatus for making garment-pads, the combination of means laying down a sheet of fibrous material, means for introducing a dry binder between the fibers of said material, means for imparting the desired shape in cross-section to said sheet, means for converting the dry binder into an active binding agent for the fibers, and means automatically cutting the pads from the sheet.

43. In an apparatus for forming garment-pads from fibrous materials, the combination of sheet-forming mechanism, skiving mechanism and pad-cutting mechanism.

44. In an apparatus for forming garment-pads from fibrous materials, the combination of means for forming a sheet of fibers, with pad-cutting mechanism.

45. In an apparatus for forming garment-pads from fibrous material, the combination of means for forming a sheet of fibers, with pad-cutting mechanism, and pad-finishing devices.

46. In an apparatus for forming garment-pads from fibrous material, the combination of means for forming a sheet of fibers, with skiving mechanism, pad-cutting mechanism, and a pad-finishing device.

47. In an apparatus of the character described, the combination of means for laying

the fibers down in sheet form, with means for subjecting said sheet to heat and pressure, said means including a moisture-carrying device.

5 48. In an apparatus of the character described, the combination of means for laying the fibers down in sheet form, a plurality of belts between which said sheet is conveyed, one of which is a moisture-carrying belt, and 10 means subjecting the sheet to heat and pressure while between said belts.

49. In an apparatus of the character described, the combination of means laying the fibers down in sheet form, means subjecting

15 said sheet to heat and pressure, forming devices for giving the sheet the desired cross-

sectional shape, and surface-finishing means for smoothing the surface of the sheet.

50. In an apparatus of the character described, the combination of means laying the material down in sheet form, forming devices for giving the sheet the desired shape in cross-section, means subjecting the sheet to heat and pressure, and means for sizing the surfaces of the sheet. 20 25

In testimony whereof I have signed this specification in the presence of two subscribing witnesses.

GUSTAV GOLDMAN.
